UNITED STATES PATENT OFFICE.

EVERETT GEORGE KAUFMAN, OF YONKERS, NEW YORK, ASSIGNOR, BY DIRECT AND MESNE ASSIGNMENTS, OF FOUR-TWELFTHS TO JOHN H. CLAUSS, OF TOLEDO, OHIO, THREE-TWELFTHS TO ULYSSES J. ULERY, OF YONKERS, NEW YORK, AND TWO-TWELFTHS TO HENRY CLAUSS, OF FREMONT, OHIO.

RAZOR-STROPPING MACHINE.

No. 825,181.

Specification of Letters Patent.

Patented July 3, 1906.

Application filed October 2, 1905. Serial No. 280,992.

To all whom it may concern:

Be it known that I, EVERETT GEORGE KAUFMAN, a citizen of the United States, and a resident of Yonkers, in the county of West- 5 chester and State of New York, have invented a new and Improved Razor-Stropping Machine, of which the following is a full, clear, and exact description.

The invention relates to razor-stropping 10 machines in which the strop is manually actuated to rock a shaft connected with the clamp employed for holding the razor in contact with the runs of the strop.

The object of the invention is to provide a 15 new and improved razor-stropping machine, more especially designed for stropping ordinary handled razors and arranged to permit convenient insertion and removal of the razor and to insure an easy rocking motion of 20 the razor-clamp to bring the cutting edge of the razor-blade into proper contact with the runs of the strop.

The invention consists of novel features 25 and parts and combinations of the same, which will be more fully described hereinafter and then pointed out in the claims.

A practical embodiment of the invention is represented in the accompanying drawings, forming a part of this specification, in which 30 similar characters of reference indicate corresponding parts in all the views.

Figure 1 is a sectional plan view of the improvement. Fig. 2 is a side elevation of the same, part of the frame being broken out; 35 and Fig. 3 is a longitudinal sectional side elevation of the same on the line 3 3 of Fig. 1.

The frame A of the razor-stropping machine is preferably made rectangular in cross-section, and in the sides A' and A² of the said 40 frame are journaled the rock-shafts B and C, connected with each other by arms B' and C', linked together, so that when the rock-shaft B is caused to rock the other rock-shaft C rocks in unison with the rock-shaft B.

On the rock-shaft C is secured a razor-clamp D, preferably in the form of two pairs 45 of spring-jaws, for receiving and holding the heel of the blade E' of the razor E, having the usual pivoted handle E², as plainly indicated in Fig. 1.

In order to permit convenient insertion

and removal of the razor while in a closed position, the inner end of the frame A is open and the side A' of the frame is provided with a recess or cut-out portion A³ adjacent to the 55 open inner end to permit of passing the razor when in a closed or folded position through the recess A³ into the casing and to engage the razor-blade E' with the razor-clamp D. After the razor-blade E' is inserted in the 60 clamp D the operator can swing the handle E² into an open position, so as to leave the blade E' within the frame A and in working position. In a like manner when it is desired to remove the razor the handle E² is swung 65 into a closed position, and then an outward pull is exerted to withdraw the blade E' from the razor-clamp D. Thus an ordinary razor can be readily inserted and removed while in a folded position, thus preventing 70 injury to the cutting edge of the razor during the inserting and removing operation, at the same time eliminating all danger of the operator cutting himself during said operation.

The strop F for stropping the razor is 75 passed over the rock-shaft B, so that the opposite runs extend on opposite sides of the razor-blade E', and when the operator alternately pulls on the ends of the runs of the strop F then the latter in traveling over the 80 rock-shaft B rocks the same, alternately in opposite directions, and as the rock-shaft C rocks in unison with the rock-shaft B it is evident that the razor-blade E' is swung alternately in engagement with the inner faces 85 of the runs of the strop F, thereby stropping the cutting edge of the razor-blade.

In order to prevent the strop F from interfering with the interlinked arms B' and C', a guard G is provided, held within the frame A 90 to inclose the said links with a view to prevent the strop from engaging the said links, especially when the same swing into an angular position, as indicated in Fig. 3. The guard G is extended into the inner open end 95 of the frame A to form a stop for the free end of the razor-blade E'. (See Fig. 1.)

The sides A' and A² of the frame A are connected with each other at their outer ends by a tie-rod H, on which fits a thimble H', abutting with its ends against the inner faces of the sides A' and A², so as to hold the same prop

erly spaced apart, and thereby prevent binding of the rock-shafts B and C in the said sides A' and A² of the frame A. The outer ends of the tie-rod H are formed into eyes H², 5 engaged by a bail I, adapted to be connected with a hook J or other similar means attached to a wall or like support, as plainly illustrated in Figs. 1 and 2. By the arrangement described the frame A is free to swing 10 when using the device in stropping the razor-blade E', as above explained, so that undue binding of the working parts is completely prevented.

The razor-stropping machine shown and 15 described is very simple and durable in construction and is not liable to get easily out of order.

Having thus described my invention, I claim as new and desire to secure by Letters 20 Patent—

1. A razor-stropping machine comprising a frame open at the inner end and having in one of its sides a recess adjacent to the said open inner end for the insertion and removal 25 of the razor while in a closed position, a tie-rod connecting the frame sides at the outer end of the frame, a bail connected with the said tie-rod outside of the frame ends, rock-shafts journaled in the frame sides and pro-

vided with arms linked together to rock the 30 shafts in unison, a razor-clamp secured on the rock-shaft located adjacent to the open inner end of the frame, and a razor-strop engaging the other rock-shaft to rock the same.

2. A razor-stropping machine comprising 35 a frame open at the inner end and having in one of its sides a recess adjacent to the said open inner end for the insertion and removal of the razor while in a closed position, a tie-rod connecting the frame sides at the outer 40 end of the frame, a bail connected with the said tie-rod outside of the frame ends, rock-shafts journaled in the frame sides and provided with arms linked together to rock the 45 shafts in unison, a razor-clamp secured on the rock-shaft located adjacent to the open inner end of the frame, a razor-strop engaging the outer rock-shaft to rock the same, and a guard in the said frame inclosing the 50 said linked arms.

In testimony whereof I have signed my name to this specification in the presence of two subscribing witnesses.

EVERETT GEORGE KAUFMAN.
